(57) **CLAIM**

The ornamental design for a pressure washer, as shown and described.

DESCRIPTION

FIG. 1 is a perspective front, top and first side view illustrating the new design.

FIG. 2 is a top plan view thereof.

FIG. 3 is a second side elevation view thereof.

FIG. 4 is a first side elevation view thereof.

FIG. 5 is a rear elevation view thereof.

FIG. 6 is a bottom plan view thereof; and,

FIG. 7 is a front elevation view thereof.

The broken line showing of details in FIGS. 1-7 is included for the purpose of showing environmental portions of the pressure washer and forms no part of the claimed design.

1 Claim, 7 Drawing Sheets
